UNITED STATES PATENT OFFICE.

CHARLES H. LEUBE, OF ALAMEDA, CALIFORNIA.

LUMINOUS PUSH-BUTTON ATTACHMENT.

1,234,550.

Specification of Letters Patent. Patented July 24, 1917.

Application filed March 21, 1917. Serial No. 156,313.

To all whom it may concern:

Be it known that I, CHARLES H. LEUBE, a citizen of Switzerland, residing at Alameda, in the county of Alameda and State of California, have invented new and useful Improvements in Luminous Push-Button Attachments, of which the following is a specification.

The object of the present invention is to provide a device which can readily be attached around a push button and which will be visible in the dark.

In the accompanying drawing, Figure 1 is a side view of the device; Fig. 2 is an enlarged longitudinal section thereof; Fig. 3 is an enlarged cross-section.

Referring to the drawing, 1 indicates a small convex piece of glass, coated on the inside, as shown at 2, with radium powder, secured thereon by any suitable adhesive. The edge of said glass piece rests against a disk 3 of rubber, leather, cloth, or any other yielding material. Said disk 3 rests against a disk 4 of brass or other suitable metal, the edge of which is soldered or otherwise secured within a cylinder 6. The cylinder 6 is of such diameter and extends on one side of said disk to a sufficient distance, as to enable it to fit around an electric push button with a fit sufficiently close to adhere firmly thereto. On the other side of said disk it is pressed inwardly, as shown at 7, to secure the glass piece in place upon the yielding disk.

The coating of radium powder renders the glass luminous in the dark.

The convex form of the glass piece is desirable since it enables the luminous attachment to be visible from any angle.

I claim:—

1. A luminous attachment for push but-

tons, comprising a cylinder of diameter and length to enable it to fit snugly around a push button, a hollow convex piece of glass secured to the outer end of the cylinder, and 45 luminous material coating the inner surface of said piece.

2. A luminous attachment for push buttons, comprising a cylinder of diameter and length to enable it to fit snugly around a 50 push button, a metal disk secured transversely in said cylinder, a hollow convex sheet of glass, the edge of which is supported by said disk, and which is secured in the outer end of the cylinder, and 55 luminous substance coating the inner surface of said sheet.

3. A luminous attachment for push buttons, comprising a cylinder of diameter and length to enable it to fit snugly around a 60 push button, a yielding disk secured transversely in said cylinder, a hollow convex sheet of glass, the edge of which is supported by said disk, and which is secured in the outer end of the cylinder, and 65 luminous substance coating the inner surface of said sheet.

4. A luminous attachment for push buttons, comprising a cylinder of diameter and length to enable it to fit snugly around a 70 push button, a metal disk secured transversely in said cylinder, a yielding disk closely adjacent to the metal disk, a hollow convex sheet of glass, the edge of which is supported by said yielding disk, and 75 which is secured in the outer end of the cylinder, and luminous substance coating the inner surface of said sheet.

CHARLES H. LEUBE.
